3 Claims. (Cl. 230—69)

The present invention relates to getter ion pumps, and has for an object, improvements therein.

In pumps working with absorption substances which in recent times are used as getter ion pumps mainly with an ionization of the residual gas but also as pure getter pumps without such ionization, vacuum is mainly produced and maintained in such a manner that getter material is continuously or intermittently vaporized and precipitated.

The getter material bonds a large part of the gases present during the movement of the atoms or molecules of the getter material due to the fact that they enter into a chemical combination with given types of gas molecules, which combination precipitates in solid form. A further part of the residual gases is absorbed by the fresh surface of the precipitated getter material. The gases which still remain, more particularly noble gases, are in many cases ionized by electron bombardment and the ions penetrate into the getter precipitate by means of a suitable field distribution.

In proportion as the getter precipitate is saturated and therefore no longer absorbs all the gas being set free in the vacuum vessel some getter material is repeatedly vaporized by means of an automatic system, said getter material precipitating on the saturated layer, forming a fresh surface thereon and taking up the residual gases to a correspondingly high degree. The new layer is however very rapidly strongly saturated in most cases because diffusion takes place from the previously saturated layer disposed thereunder into the new layer. Mainly the gases which were taken up by the old layer penetrate into the new layer and cause a rapid saturation.

The invention has for its object to remove or minimise this drawback, and according thereto, at least after admission of air in the pump but preferably also at certain periods of time during the operation, a substance is vaporized on the precipitated layer of the gettering material which prevents or at least strongly reduces a diffusion of gas molecules or vapour molecules into the freshly vaporized layer, said gas or vapour molecules having been taken up by the existing layer of getter material, especially of titanium metal.

For this purpose there may be used metals which vaporize well, which show at normal temperature very little tendency to chemical reactions and are in part designated as "noble metals." Such metals are gold, silver, platinum, ruthenium, rhodium, palladium, osmium and iridium. However, other metals also which are to a large extent chemically stable such as copper, nickel, cadmium, and tantalum may be used for this purpose. In the cold state, the metal used should show no diffusion or only a very small diffusion of gas molecules or gas ions through the metal. However, in the cold state it should also show no diffusion or only a very small diffusion into the already present titanium layer or a diffusion of the titanium in the vaporized metal. In this connection silver in particular has proved excellent in practice, only a thin layer thereof substantially preventing any gas diffusion.

However, metal compounds also, mainly fluorides such as magnesium fluoride or thorium fluoride may be advantageously used for this purpose. The low electrical conductivity of these compounds is not troublesome because the layers are very thin and the electrical current to be conducted is relatively small.

2

The advantage of the proposal made here consists in a many times better utilisation of the getter material present in the pump. In order to maintain a given vacuum for a long duration a substantially smaller getter supply will therefore be required in the pump.

However, the advantage of the invention is mainly noticeable when the pump must be flooded and the getter layer was completely transformed into the oxide, nitride etc., by the atmospheric gases. Thereafter, when the operation is again started relatively thick new getter layers are necessary in order to reduce the diffusion now occurring, to an extent such as to ensure a sufficient pump action. Hitherto it was therefore necessary to remove the getter precipitate present substantially wholly before flooding.

As a result of the present invention this is no longer necessary. When starting the operation a substance hindering diffusion, for example silver, is first vaporized and thereafter the getter material. It has been shown that the pump then immediately reaches its normal pump action without it being necessary to vaporize more getter material than is usual during the operation.

In order that the invention shall be more clearly understood, reference will now be made to the accompanying drawings which show an embodiment thereof by way of example and in which:

FIGURE 1 shows a getter ion pump according to the present invention in longitudinal section, and

FIGURE 2 shows the layers vaporized on the wall, to an enlarged scale.

As shown in FIGURE 1, a getter ion pump consists of a tubular body 1, which has for example an internal diameter of 20 centimetres and is made of stainless steel. This tubular part 1 carries at one end a flange 2 which is connected by means of a metallic seal 3 to a flange 4 of a high vacuum vessel 5. The other end of the tubular part 1 is sealed by a plate 6. A pipe 7 leads from the body 1 through a valve 8 to a single-stage or multi-stage vacuum pump schematically illustrated at 9.

Several electrical conductors lead through the tubular part 1 and the base plate, said conductors being insulated from the electrically grounded pump body by insulators 10 inserted in the wall of the body 1 in a vacuum-tight manner.

Two vaporizers 11 and 12 are situated within the pump body, each of said vaporizers consisting of a heating wire, for example, made of tungsten. The tungsten heater wire of vaporizer 11 is surrounded by a thinner titanium wire, and that of the vaporizer 12 is surrounded with a silver wire. An alternating current is passed to the vaporizers 11 and 12 by the leads 13 and 14 respectively as shown in the drawing, said alternating current, on operation of switch 15 or 16, heating the tungsten wires in a known manner to such a temperature that the titanium or silver coiled on it vaporizes. Further vaporizers (not shown) are provided for titanium, in the case when the pump is operated for a longer time.

Also within the pump body is situated a grid 25 having the shape of a circular cylinder, said grid being given a positive voltage relative to the pump body 1 by means of the conductor 26, and being held by insulators 27. Approximately in the axis of the pump is situated a heating wire 28 of tungsten, to which a current may be supplied by means of the conductors 29. On operation of the switch 30, the heating wire 28 is brought to a temperature such that it emits electrons. In the circuit shown it is at earth potential, like the pump housing, but it may have a lower voltage relative to the pump body.

The pump works in the following manner:

The vacuum vessel 5 and the internal chamber of the pump are first evacuated by the vacuum pumps 9, the

valve 8 being open. In order to remove the gases adsorbed on the walls, the walls of the vessel 5 and also of the pump are then brought to a higher temperature for example to 200° C. This may be effected in any manner which is familiar to any person skilled in vacuum technique, for example by heating coils (not shown) which for this purpose are applied on the external side of the vessel and of the pump. After a certain time the adsorbed amounts of gas are removed to a large extent.

The valve 8 is then closed and the vacuum pump 9 is switched off. The vaporizer 11 is now switched on and a given first amount of titanium is vaporized which precipitates on the pump wall 1 and reduces the pressure strongly by gettering. Hereby nearly all gases which react chemically easily such as oxygen, nitrogen and hydrogen etc. are to a large extent removed.

Then the heating coil 28 is switched on and a positive voltage is applied to the grid 25. The electrons produced by the heating element 28 fly over to the grid 25, pass to a large extent through its meshes and before reaching the wall 1 are reflected by the field prevailing there. They thus return again to the internal chamber of the grid 25 and carry out an oscillatory movement in the manner described.

The electrons impinge in their long flight paths upon the residual molecules of the vacuum and ionize them. The thus formed ions, mainly ions of noble gases are accelerated through the electrical field between the grid 25 and the wall 1 and are shot in the titanium precipitate on this wall. This phenomenon leads to a further very strong reduction of the pressure.

After a certain time, the take-up capacity of the titanium precipitate is exhausted or at least strongly reduced, and therefore the pressure no longer drops further, but shows a tendency to rise. Then some titanium is again vaporized on the saturated precipitate. This second titanium layer is also saturated after a given time and therefore the vaporization must be repeated.

It is not essential for the work of a pump that individual discrete titanium layers are precipitated in given intervals of time; this illustration was only chosen for the purpose of a better understanding of the processes in the pump. The titanium could, on the contrary, be practically continuously vaporized. Then also there occurs a saturation of the layers and therefore the rates of the vaporization must be chosen to be suitably large.

However, as experience shows, the take-up capacity of the newly produced titanium layers is smaller as would be expected according to known chemical and physical considerations. This is obviously due to the fact that from the already saturated layers a part of the gases which are bound there, probably mainly hydrogen diffuses in the newly vaporized layer and saturates it to some extent beforehand. This reduces the effectiveness of these layers. In order to prevent this to the largest extent pos-

5 sible, a diffusion-hindering layer is vaporized from time to time by switching the vaporizer 12 on and applying on it new titanium precipitates.

The action of such a layer of silver is shown enlarged in FIGURE 2.

Several saturated titanium layers 35 in which the already combined atoms are shown by points are situated on the internal side of the pump wall 1. The silver layer 36 is applied to these layers on which again a titanium layer 37 is vaporized. The silver layer 36 prevents the molecules from diffusing from the lower layers 35 directly into the new layer 37. The layer 37 is therefore available for the pressure reduction with all its absorption capacity.

I claim:

1. A vacuum pump comprising a housing having a pump chamber with surfaces for receiving a getter material thereon and including an outlet port and an inlet port, means for ionizing gas within said pump chamber, means for directing the travel of said ionized gas toward said surfaces, means for vaporizing a first getter material in said chamber for burying said ions upon said surfaces, means for vaporizing a second gettering material after a plurality of layers of said first material have accumulated upon said surfaces, said second material comprising a substance which inhibits the diffusion of gas molecules therethrough.

2. A vacuum pump comprising a housing having a pump chamber with surfaces for receiving a getter material thereon and including an outlet port and an inlet port, means for ionizing gas within said pump chamber, means for directing the travel of said ionized gas toward said surfaces, means for vaporizing a first getter material in said chamber for burying said ions upon said surfaces, means for vaporizing a second gettering material after a plurality of layers of said first material have accumulated upon said surfaces, said second material comprising a metal chosen from the group gold, silver, platinum, ruthenium, rhodium, palladium, osmium, and iridium and which inhibits the diffusion of gas molecules therethrough.

3. A vacuum pump comprising a housing having a pump chamber with surfaces for receiving a getter material thereon and including an outlet port and an inlet port, means for ionizing gas within said pump chamber, means for directing the travel of said ionized gas toward said surfaces, means for vaporizing a first getter material in said chamber for burying said ions upon said surfaces, means for vaporizing a second gettering material after a plurality of layers of said first material have accumulated upon said surfaces, said second material comprising a metal compound chosen from the group magnesium fluoride and thorium fluoride and which inhibits the diffusion of gas molecules therethrough.
